COMPARTMENT DOOR LATCH

Edward N. Jacobi, Milwaukee, Wis., assignor to
 Briggs & Stratton Corporation, Milwaukee,
 Wis., a corporation of Delaware

Application May 10, 1938, Serial No. 207,037

15 Claims. (Cl. 70—150)

This invention relates to door latching mechanism, and refers particularly to improvements in latching mechanism for glove compartment doors such as illustrated in the copending application of Edward N. Jacobi, Serial No. 178,954, filed December 9, 1937.

Latching mechanisms of this type comprise a hook bolt pivotally mounted from the door in position to engage and snap past a stationary keeper as the door is closed and to hold the door closed by spring tension, suitable key controlled locking mechanism generally being provided to lock the bolt against movement necessary for opening the door.

With this past construction, it was difficult to balance the spring tension of the hook bolt, as the tension had to be light enough to permit the door to be pulled open against the latch spring by as much force as can be exerted through the thumb and forefinger grasping a relatively small knob, and strong enough to hold the door closed against vibration and bouncing as the car moved over the road.

The present invention, therefore, contemplates as its primary object the provision of easily operated means for positively disengaging the hook bolt from the keeper preparatory to opening the door.

More specifically it is an object of this invention to provide means for releasing the hook bolt from the keeper by pressing a lever or other suitable actuator toward the side of the customary knob so that the release of the hook bolt from the keeper is easily effected as an incident to grasping the knob between the thumb and forefinger in the customary manner.

Another object of this invention is to provide a bolt releasing device for the purpose described which is so designed that its application to a door latching mechanism of this character is effected without material alteration in its design or construction.

With the above and other objects in view which will appear as the description proceeds, this invention resides in the novel construction, combination and arrangement of parts substantially as hereinafter described, and more particularly defined by the appended claims, it being understood that such changes in the precise embodiment of the hereindisclosed invention may be made as come within the scope of the claims.

The accompanying drawings illustrate one complete example of the physical embodiment of the invention constructed in accordance with the

best mode so far devised for the practical application of the principles thereof, and in which:

Figure 1 is a perspective view illustrating the application of this invention to an automobile glove compartment door;

Figure 2 is a horizontal sectional view through the latch mechanism, with parts broken away and in section and with the hook bolt in its operative keeper engaging position;

Figure 3 is a view similar to Figure 2, but illustrating the manner in which the hook bolt is positively swung out of keeper engaging position;

Figure 4 is a sectional view through the door and its frame taken through Figure 1 on the plane of the line 4—4;

Figure 5 is a perspective view of the hook bolt per se;

Figure 6 is a perspective view showing the inner end of the lock casing which serves as the body for the mechanism;

Figure 7 is a perspective view of the bolt releasing device per se, shown separated from the latch mechanism; and

Figure 8 is a perspective view of the rear portion of the lock cylinder.

Referring now particularly to the accompanying drawings in which like numerals indicate like parts throughout the several views, the numeral 5 designates an instrument panel of an automobile, in back of which a glove compartment 6 is mounted. The open front of this compartment is adapted to be closed by a door 7 hinged along its bottom edge. The door 7 is held closed by a latch mechanism, indicated generally by the numeral 8, which is so designed that it secures the door closed upon slamming the door shut and also locks the same against opening when desired by means of a key controlled lock.

To this end the latch mechanism comprises a hook bolt 9 pivotally mounted from the upper free edge of the door, in a manner to be hereinafter described, in position to engage a stationary keeper 10 suitably fixed to the ceiling of the glove compartment. In the present instance, the hook bolt is pivotally supported on the inner end of a cylinder lock casing 11 which passes through a hole 12 in the bottom of an elongated depression 13 formed in the door.

The outer end of the casing 11 passes through a knob 14 whose inner end is shaped to fit the bottom of the depression 13, and whose outer end is flaringly enlarged to provide a comfortable grip for the thumb and forefinger. Preferably, the depression 13 is deep enough to have the entire knob disposed therein.

The assembled casing and knob are held in place by a cap 15 fitted over the inner end of the casing and drawn toward the casing by a screw 16 to clamp the bottom wall of the depression 13 between it and the knob. A dowel pin 17 projecting from the inner end of the casing and passing through a hole in the cap aids in maintaining the cap and casing properly assembled.

To pivotally mount the hook bolt, the inner 10 end of the casing is diametrically recessed as at 18 to receive the bolt, and the side walls of this recess have sockets 19 to receive pivot pins 20 projecting from opposite sides of the hook bolt and preferably formed as an integral part thereof. 15 The pivot pins 20 are engageable in the sockets 19 in the manner described in detail in the aforesaid copending application.

A compression spring 21 confined between the underside of the hook bolt and a spring seat 22 20 closing the bottom of the recess 18, yieldingly urges the outer end of the hook bolt upwardly to a keeper engaging position. Inasmuch as the upper edge 23 of the hook bolt is inclined, it follows that in closing the door, the hook bolt 25 is cammed past the keeper to snap in back of it and hold the door closed when slammed shut.

If desired, the door may be locked shut by securing the hook bolt against movement out of its keeper engaging position. This is accomplished 30 by turning a key controlled lock cylinder 24 rotatably mounted in the casing 11 to a position at which an eccentrically positioned rearwardly extending locking lug 24' carried by the cylinder (see Figure 8) moves over a projection 25 on the 35 inner end of the hook bolt.

To disengage the hook bolt from the keeper easily and with a minimum of effort, a wedge-shaped link 26 is slidable endwise in a transverse slot 27 in the inner end of the casing 11, in position to move across a cam surface 28 on the hook bolt. As the link moves across the cam surface 28, it swings the bolt against the action of its 40 spring away from its keeper engaging position.

Motion is imparted to the link 26 by means of 45 a lever 29 pivotally connected at its inner end with the link. This lever projects through a hole 30 in the door carried wall 13 so that its outer end is adjacent to the side of the knob 14. Medially of its ends, the lever carries a lug 31 50 which engages the side of the casing 11 made accessible by a slot 32 through the side of the knob to provide a fulcrum about which the lever may be rocked to pull the link across the cam surface 28.

By having the lever 29 fulcrumed on the point 55 of the rounded lug 31, sliding movement of the fulcrum point necessitated by the fact that the link 26 is constrained to slide in a fixed plane transversely of the casing is permitted. If the lever were pivoted from the casing, either its 60 pivotal mounting or its connection with the link 26 would have to have a degree of play which is objectionable.

Also, this manner of mounting the lever enables the knob 14 to be slipped onto the casing 11 65 at the final installation so that the knobs may be matched with other hardware of the automobile. This follows from the fact that the lever is free to be swung around its pivotal connection with the link 36 until it lies alongside the hook bolt 9 and wholly within the confines of the circumference of the casing 11. With the lever in this 70 position, the knob may be slipped onto the casing.

It is also to be noted that the sliding wedge 75 shaped link or cam 26 is held assembled with

the casing by the action of the spring 21 acting through the cam surface 28 on the hook bolt. By retracting the hook bolt against the action of its spring 21 beyond its normal limit, the link or cam may be withdrawn from the slot 27; but, of course, this is possible only when the entire device is removed from the door.

The outer end 33 of the lever is enlarged to provide a convenient grip engageable by the thumb in the natural manner of grasping the knob, as shown in Figure 1, and by virtue of the increased leverage provided by the long outer end of the lever, a comparatively light force applied in this manner positively disengages the hook bolt from the keeper.

Upon release of the lever, a spring 34 interposed between the lever and the side of the casing 11 rocks the lever about the engagement of its back edge with the bottom of the hole 30 to return the lever and the link 26 to their normal positions permitting the hook bolt to be spring propelled to keeper engaging position.

From the foregoing description taken in connection with the accompanying drawings, it will be readily apparent to those skilled in the art that this invention entirely obviates the need for critical tensioning of the latch spring by which the hook bolt is urged to its keeper engaging position, and permits a heavy spring tension to be used to insure against having the door open accidentally, without making it difficult for anyone to pull the door open.

What I claim as my invention is:

1. Door latching mechanism comprising: a hook bolt; means pivotally mounting the hook bolt from the door; a spring yieldingly urging the hook bolt to its operative latching position; a knob on the outside of the door by which a pull may be applied to the door; and means for retracting the hook bolt preparatory to opening the door comprising, a member movable transversely to the plane of motion of the hook bolt and constrained to move in a fixed path; a cam connection between said member and the hook bolt operable upon movement of said member in one direction to swing the hook bolt against the action of its spring; and a lever connected at its inner end with said member and fulcrumed at an intermediate point alongside of the knob so that movement of the outer end of the lever toward the knob moves said member in a direction to retract the hook bolt.

2. Door latching mechanism comprising: a hook bolt; means pivotally mounting the hook bolt from the door, a spring yieldingly urging the hook bolt to its operative latching position; a knob fixed on the front of the door to provide means for imparting a pull on the door; a member behind the door constrained to move in a fixed path transversely to the plane of motion of the pivoted hook bolt; a cam connection between said member and the hook bolt whereby motion of said member in one direction swings the hook bolt against the action of its spring to retract the same; a lever having its inner end pivotally connected with said member and projecting through a hole in the door alongside the knob, the edge of the hole providing a fulcrum support for the lever; a spring acting on the outer end of the lever to swing the lever on said fulcrum support in a direction holding the bolt retracting member in an inactive position; and another fulcrum support for the opposite side of the lever receiving support from the knob whereby the outer end of said lever may be de-

pressed toward the side of the knob to draw the bolt retracting member in a direction to effect retraction of the bolt.

3. Door latching mechanism of the character described comprising: a hook bolt; means for pivotally mounting the hook bolt on the door including, a lock casing extending through a hole in the door; a knob encircling the outer end of the lock casing; means on the inner end of the lock casing coacting with the knob to clamp the door between it and the knob; a pivotal support for the hook bolt on the inner end of the lock casing; a cylinder in the lock casing; a connection between the cylinder and the bolt whereby the bolt may be locked in its operative latching position; a member slidably mounted in the inner end of the lock casing to move in a fixed path transverse to the plane of motion of the hook bolt; cam means for swinging the hook bolt on its pivotal support in a retracting direction upon endwise motion of said member in one direction; and means mounted adjacent to the knob for imparting bolt retracting motion to said member.

4. Door latching mechanism of the character described comprising: a hook bolt; means for pivotally mounting the hook bolt on the door including, a lock casing extending through a hole in the door; a knob encircling the outer end of the lock casing; means on the inner end of the lock casing coacting with the knob to clamp the door between it and the knob; a pivotal support for the hook bolt on the inner end of the lock casing; a cylinder in the lock casing; a connection between the cylinder and the bolt whereby the bolt may be locked in its operative latching position; a member slidably mounted in the inner end of the lock casing to move in a fixed path transverse to the plane of motion of the hook bolt; cam means for swinging the hook bolt on its pivotal support in a retracting direction upon endwise motion of said member in one direction; a lever member connected at its inner end with said bolt retracting member and projecting through a hole in the door to have its outer end in juxtaposition to the side of the knob; and means providing a fulcrum support for the medial portion of said lever so that the outer end of the lever is depressible toward the side of the bolt to impart a bolt retracting motion to said sliding member.

5. Door latching mechanism of the character described comprising: a hook bolt; means for pivotally mounting the hook bolt on the door including, a lock casing extending through a hole in the door; a knob encircling the outer end of the lock casing; means on the inner end of the lock casing coacting with the knob to clamp the door between it and the knob; a pivotal support for the hook bolt on the inner end of the lock casing; a cylinder in the lock casing; a connection between the cylinder and the bolt whereby the bolt may be locked in its operative latching position; a member slidably mounted in the inner end of the lock casing to move in a fixed path transverse to the plane of motion of the hook bolt; cam means for swinging the hook bolt on its pivotal support in a retracting direction upon endwise motion of said member in one direction; a part depressible toward the side of the knob; means yieldingly urging said part away from the knob; and a connection between said part and the bolt retracting member whereby depression of said part toward the side of the knob draws the bolt retracting member in a direction to retract the bolt.

6. In a door latching mechanism of the char-

acter described: a lock casing having an enlarged head; a hook bolt carried by the lock casing biased to an operative position; a knob bored to receive the lock casing, said bore being smaller than the enlarged head of the lock casing so that the knob is capable of assembly with the casing only from the rear thereof; a cam transversely movable in the rear portion of the lock casing and engageable with the hook bolt for moving it out of its operative position; a lever pivotally connected with the cam and having its free end portion disposed alongside the knob; and means at an intermediate portion of the lever providing a fulcrum about which the lever may be rocked to actuate the cam, said connection between the lever and the cam enabling the lever to be swung rearwardly within the confines of the circumference of the lock casing to enable the knob to be assembled with the casing after assembly of the lever with the cam.

7. Door latch mechanism comprising: a supporting member; a hook bolt pivotally mounted on said member; a spring yieldingly urging the hook bolt to an operative latching position; means for retracting the hook bolt including a manually operable actuator; and a cam connected with the actuator and slidably carried by the supporting member in position to engage a portion of the hook bolt to retract the bolt, the connection between the cam and the bolt being such that the bolt spring acting through the bolt retains the cam and its actuator assembled with the supporting member.

8. Door latching mechanism comprising: a supporting member mounted on the door; a hook bolt pivotally carried by said supporting member on the inside of the door; a spring for yieldingly maintaining the hook bolt in its operative latching position; a knob on the exterior of the door by which a pull may be exerted on the door; depressible means adjacent to the knob; and a part movably supported by the supporting member and connected with said depressible means and engaging the hook bolt for retracting the hook bolt upon depression of said means, the connection of said part with the hook bolt being such that the bolt spring acting through the bolt retains said part and the depressible means assembled with the supporting member.

9. Door latching mechanism comprising: a supporting member mounted on the door; a hook bolt pivotally mounted on the supporting member; a spring yieldingly urging the hook bolt to its operative latching position; a knob on the exterior of the door by which a pull may be applied to the door; a member slidably mounted on said supporting member and constrained to move in a fixed path adjacent to the hook bolt; a cam connection between said member and the hook bolt operable upon movement of said member in one direction to swing the hook bolt against the action of its spring; and an actuator connected with said slidable member and having a part disposed adjacent to the side of the knob, said cam connection being such that the bolt spring acting therethrough normally maintains the slidable member and its actuator assembled with the supporting member while enabling disassembly of said parts upon motion of the hook bolt beyond its normal retracted position.

10. In a door latching mechanism: a supporting member, said supporting member having a recess and a transverse slot communicating with said recess; a hook bolt having a portion thereof disposed in said recess; a separable pivot connec-

tion between said portion of the hook bolt and the walls of the recess; a spring acting on the hook bolt for yieldingly maintaining the same in its operative latching position; and a bolt retracting member slidable in the slot of the supporting member and engaging an adjacent portion of the hook bolt to apply a retracting force thereon, said bolt retracting member preventing disassembly of the hook bolt from the supporting member.

11. A door latching mechanism comprising: a supporting member having an open recess and having a transverse slot communicating with the recess; a hook bolt having a portion disposed in said recess; cooperating means on said portion of the hook bolt and the adjacent walls of the recess providing a separable pivotal connection by which the bolt is pivotally mounted on the supporting member; a spring yieldingly maintaining the bolt in its operative latching position; and a retracting element slidable in said slot and operable to retract the bolt against the action of its spring, the connection between said bolt retracting element and the bolt being such that said parts mutually retain each other assembled with the supporting member.

12. A door latching mechanism comprising: a supporting member having an open recess and having a transverse slot communicating with the recess; a hook bolt having a portion disposed in said recess; cooperating means on said portion of the hook bolt and the adjacent walls of the recess providing a separable pivotal connection by which the bolt is pivotally mounted on the supporting member; a spring yieldingly maintaining the bolt in its operative latching position; and a retracting element slidable in said slot and operable to retract the bolt against the action of its spring, the connection between said

bolt retracting element and the bolt being such that said parts mutually retain each other assembled with the supporting member while enabling disassembly of the retracting element and the hook bolt from the supporting member by movement of the bolt beyond its normal retracted position against the action of its spring.

13. A door latch comprising: a knob; a hook bolt having trunnions; half bearings in the knob to receive the trunnions; a cam for retracting the hook bolt mounted in the knob in a position that presses the hook bolt trunnions into the half bearings by the cam engaging pressure; and an operating handle adjacent to the knob and connected to the cam.

14. A door latch comprising: a knob; a hook bolt having trunnions; half bearings in the knob to receive the trunnions; a cam for retracting the hook bolt mounted in the knob in a position that presses the hook bolt trunnions into the half bearings by the cam engaging pressure; an operating handle adjacent to the knob and connected with the cam; and cooperating stops between the door, the knob, and the operating handle to retain the cam and the operating handle assembled in operating relation with the knob and hook bolt.

15. A door latch comprising: a knob having a slot; a bolt mounted thereon adjacent to the slot; a cam slidable in the slot; a cooperating cam surface on the bolt whereby the bolt is retractile by endwise motion of the cam; a handle lever connected with the cam and having a projecting fulcrum point adapted to bear against the side of the knob; and said door wall having a slot to guide the sides of the handle lever and to limit its movement away from the knob.

EDWARD N. JACOBI.
